UNITED STATES PATENT OFFICE.

FRANK KATZ, OF NEW YORK, N. Y.

CREASE-RETAINER FOR HATS.

1,251,045.

Specification of Letters Patent. Patented Dec. 25, 1917.

Application filed September 24, 1917. Serial No. 192,844.

To all whom it may concern:

Be it known that I, FRANK KATZ, a citizen of the United States, residing at No. 46 Fort Washington Ave., New York, in the 5 county and State of New York, have invented certain new and useful Improvements in Crease-Retainers for Hats; and I do hereby declare the following to be a full, clear, and exact description of the invention, such 10 as will enable others skilled in the art to which it appertains to make and use the same.

My present invention has relation to an improvement in soft felt hats of the kind 15 which is longitudinally creased at the top, and the object of the invention is to supply a hat of this kind which can be worn either with a deep crease securely formed and maintained or with the two sides of the 20 crown parted. By the use of my invention the sides of the crown can be instantly united to form the deep central crease, or may as easily be parted, and either operation can be performed without removing the hat 25 from the head.

Figure 1 of the accompanying drawing shows the hat in elevation with the sides united, and Fig. 2 shows the same with parted sides.

30 The two sides of the crown are shown at 1 and 2, and in Fig. 1 they are united to

form the deep crease 3, by bringing together the opposed faces of the crown sides. These faces are provided respectively with the two halves 4 and 5 of an ordinary glove 35 fastener, and it is only necessary to pinch the sides together while on the head to close the fastener and secure the crown sides together to firmly maintain the crease. When it is preferred to wear the hat as shown in 40 Fig. 2, the glove fastener can be opened by a simple pull.

So far as I am aware, devices for securing the creases of soft hats have hitherto comprised separable springs or plates which 45 worked from inside of the hat and required the hat to be removed from the head where a change was desired. The improvement involved in my invention is obvious.

In my claim, the term "glove fastener" 50 is to be understood as covering any equivalent device, wherein one member can be pressed into the other to make a fastening effective.

What I claim is:—

A soft hat having two crown sides provided on their opposed faces with the two halves of a glove fastener so placed as to meet and fasten when the crown sides are pinched together.

55 In testimony whereof, I affix my signature.
FRANK KATZ.
